North Manchester, Ind., a partnership of
Indiana

Application September 25, 1940, Serial No. 358,217

3 Claims. (Cl. 155—86)

This invention relates to improvements in that type of chairs adapted to be used in large auditoriums, operas, churches and the like, wherein the chairs are arranged in either straight or circular rows and fixed to the floor with the end of one chair joining the end of an adjacent chair.

The object of my invention is to provide an improved chair comprising a back and seat portion and leg and arm portions for supporting the back and seat portions, wherein the leg and arm portions may be fixed to the floor in either straight or circular rows and spaced apart a proper distance to receive between them the back and seat portions, and to provide means whereby the back and seat portions may be easily and quickly attached or removed after the arm and leg portions have been positioned.

A further object of my invention is to provide in a chair of the type above described, means wherein the seats may be arranged in circular rows of various radii without altering the construction of the chair, and at the same time provide seat construction of neat and pleasing appearance.

A further object of my invention is to provide in a chair of the type above described, improved means for automatically returning the seats to their upright positions when not in use.

A further object is to provide an improved chair wherein the seat portion, back portion, and the means for supporting the seat portion and back portion from the leg and arm portion may be assembled as a unit ready to be placed in position after the leg and arm portions have been permanently set, with means for easily and quickly attaching the seat and back portions thereto, and in connection therewith, means for adjusting the angle of the back portion relative to the leg and arm portions, to vary the inclination of said back portion.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is an end elevation of my improved chair, a portion of which is shown in section on the line 1—1 of Figure 2;

Figure 2 is an enlarged detail sectional view taken on the line 2—2 of Figure 1;

Figure 3 is an enlarged detail sectional view taken on the line 3—3 of Figure 2;

Figure 4 is an enlarged detail sectional view taken on the line 4—4 of Figure 2;

Figure 5 is an enlarged detail sectional view taken on the line 5—5 of Figure 1;

Figure 6 is a perspective view of the inner surface of one of the side plates for supporting the seat and back sections, showing therewith the plate for supporting and adjustably mounting one end of the back section thereto; and

Figure 7 is a perspective view of the outer face of said supporting plate.

The numeral 10 indicates the leg and arm section, which I shall term for the sake of convenience the "leg section," comprising a frame formed of cast metal, having upright front legs 11 and back leg members 12, the upper ends of said leg members being connected by an arm-supporting bar 13, while the central portion of said leg members is connected with a cross bar 14. The lower ends of the legs 11 and 12 have flange portions 15a by means of which the legs may be secured to the floor.

The back edge of the upper portion of the leg member 12 is substantially semi-circular in cross section so as to provide a convex surface 15 to which the supporting plates 16 and 17 may be detachably secured. The back edge of the plate 16 is provided with a curved flange portion 18 adapted to be supported against the convexed surface 15, while the back edge of the plate 17 is provided with a curved flange 19 adapted to overlap the curved portion 18 in the manner clearly illustrated in Figures 2 and 5. The upper ends of the curved portions 18 and 19 are provided with openings 20 for receiving a set screw 21. A short cover plate 22 is provided between the member 19 and the head of the screw 21 to cover the slots 20. The lower ends of the curved portions 18 and 19 are also provided with slots 23 arranged to permit vertical adjustment as well as circumferential or circular adjustment.

A plate 24 is provided for covering said slots 23, and a set screw 25 provides means for adjustably securing the lower ends of the plates 16 and 17 to the back edge of the leg portions 12. Each of the leg portions 12 is provided with a set of supporting plates 16 and 17, and are provided with means whereby the forward edges of the plates 16 and 17 may be adjusted toward and from each other and toward and from the inwardly extending flange 26 of the leg 10 and inside of the laterally extending flanges 27 of said leg, as clearly illustrated in Figure 2.

The plates 16 and 17 provide means for supporting the seat 28 and the back section 29, the lower and forward edge of each of the plates 16 and 17 having an opening 30 and a sleeve

31 surrounding said opening and extending inwardly. Extending through the said opening 31 and said sleeves of two corresponding sections 16 and 17 is a seat-supporting shaft 32 for supporting the seat member 28, the bottom of said seat member 28 being secured thereto by means of suitable brackets 33 which are fixed to said shaft and to the seat portion, the said shaft providing means whereby the seat member may be tilted from a substantially horizontal position to a substantially vertical position, or vice versa. The sleeve 31 is provided with a fibre bushing 34 for carrying the said shaft 32, the outer end of the shaft being provided with a washer 35 and a nut 36 for tying the supporting plates and the seat portion together with the supports 16 and 17 parallel.

Surrounding the sleeve 31 concentrically is a second sleeve 37 of a larger diameter to form a space 38 and to form a housing for the spring 39 which is wound around the sleeve 31 and having one end anchored to a bolt 40 extending through the sleeve 37 in the manner clearly illustrated in Figure 3. The other end of the spring 39 is provided with a loop 41 which is adapted to engage a pin 42 mounted in a disc 43 fixed to and carried by the shaft 32, said disc 43 also being supported substantially within the sleeve 31. Each end of the shaft 32 is provided with a spring 39 which is so wound as to tend to move the seat from a horizontal position to substantially a vertical position.

For limiting the movement of the seat as it moves to its vertical position I have provided a semi-circular flat spring 44, one end of which is secured to the housing 37 by rivets 45, the other end of said spring 44 being provided with an inwardly extending lug 46 for engaging the pin 42 when the seat is in its vertical position, the said spring 44 serving to also act as a shock absorber.

For limiting the movement of the seat as it is moved to its horizontal position, I have provided in each of the plates 16 and 17 an opening 47 for receiving a stop pin 48, having one end provided with laterally projecting flanges 49 adapted to engage the outer surface of the plates 16 and 17, said flanges being welded or otherwise secured thereto. The back edge of the under surface of the seat is provided with lugs 50 for engaging the lugs 48 in the manner clearly illustrated in Figure 2.

The inner surface of each of the plates 16 and 17 is provided with a back-supporting plate 51 and pivotally connected to said plate by a pivot 52, the upper end of the plate being provided with a bolt 53 adapted to pass through a slot 54 having one of its edges provided with notches 55 for receiving the said bolt 53, thus providing means whereby the top ends of the plates 51 may be adjusted forwardly or rearwardly, the back edge of each of the plates 51 being provided with a curved flange 56 to which the back section 29 is secured either by riveting or welding. In assembling the seat 28 and the supporting members 16 and 17 are secured together in operative relation by means of the shaft 32 with the plates 51 inside of said supports, the curved portions 56 being welded to the back 29, the pivots 52 serving to pivot the back 29 and the member 51 to the supports 16 and 17, and the shaft 32 serving to tie the lower ends of the supports together while the back 29 and the plate 51 serve to tie the back and central portion of said supports together, so that the back

29, supporting plates 16 and 17, together with the seat 28 form a unit that I have termed a seat "section," each section having outwardly projecting curved portions 19 and 18 by means of which the seat sections are secured to the leg portions by suitable set screws.

By this construction it will be seen that the seat comprises leg sections 10 which may be first fastened to the floor with the plane of the leg sections within the radius of the circular arc in which the seats are to be mounted, and spaced apart such a distance as to receive between them the seat sections which may be placed in position by simply placing the flanges 18 and 19 of two adjoining seat sections adjacent to the back edge of the leg section common to both of said seat sections, and then placing the set screws 21 and 25 in the slots 20 and 23. From the construction above described it will be seen that the side plates 16 and 17 of a given seat section will always be parallel and that when the said seat section is in position, the forward edges of the said side plates will automatically assume their proper position within the flanges 27 of the front leg portion.

In the setting of the leg sections, if the seats are placed in arcuate rows the workman simply draws on the floor a line having the proper radius through which a vertical line from the back edges of the leg members 12 would fall, then marks on the said line points spaced apart a distance equal to the distance between the centers of the convexed surfaces of the back edges of the legs 12, after which the leg portions may then be placed immediately on these marks with the leg sections in radial upright planes from said marks, after which the seat sections may then be placed in position. In like manner, a second row of seats may be placed concentrically with the first row and wherein the same seat construction is adapted to be placed in all of said rows, regardless of the length of the radii, without any alteration or changes. The seat-supporting plates will automatically adjust their positions one relative to the other.

Thus, it will be seen I have provided a simple and efficient seat construction wherein the back and seat portions and their supporting plates may be assembled as a unit in a factory and delivered to the auditorium in which the seats are to be placed, ready to be installed, with the leg sections as other units, wherein the leg sections may first be installed and the seat sections thereafter placed in position and wherein the workman needs to pay no attention as to adjustment of the elements any other than placing the curved sections of the side plates in position on the back edges of the leg members and locking the same in position by means of the set screws.

It will further be seen I have provided means whereby the seat sections will be automatically elevated to vertical position when in use, wherein the seats will always be folded up to permit free access to and from the seats.

I claim as my invention:

1. In a device of the class described, a pair of parallel supporting side plates, a seat between the lower ends of said plates, a shaft fixing the lower ends of said supports in parallelism and in spaced relation with each other, means mounting the seat on said shaft, a back, means securing said back to and between said supporting plates wherein the supporting plates and said seat and back form an assembly unit, a leg portion adjacent to each supporting plate, and means for ad-

justably fixing the back edges of said unit to the back edges of the corresponding leg portions, wherein the angularity of the leg portions may be varied in respect to the corresponding supporting plates.

2. In a device of the class described, a pair of parallel supporting plates, a seat between the lower ends of said plates, a shaft fixing the lower ends of said supporting plates in spaced relation with each other, means mounting the seat on said shaft, a back having each of its upright edges provided with a forwardly extending plate, means pivotally connecting the said forwardly extending plates to said supporting plates, wherein in the upper end of said back may be adjusted forwardly and rearwardly, means for locking said back in any one of its adjusted positions, a shaft connecting the lower ends of said supporting plates, a seat supported by said shaft wherein the supporting plates, the back, the shaft and the seat form an assembled unit, a leg section adjacent to the side of each supporting plate, and

means adjustably securing the back edges of said supporting plates to the back edges of the corresponding leg portion.

3. In a device of the class described, a pair of spaced supporting plates, the back edge of each of said plates having an outwardly curved flange, a seat between the lower ends of said plates, a shaft fixing the lower ends of said supporting plates substantially in parallelism, means mounting the seat on said shaft, a back having each of its upright edges provided with a forwardly extending plate, means pivotally connecting said forwardly extending plates to corresponding and adjacent supporting plates wherein the upper end of said back may be adjusted forwardly and rearwardly, means for locking said back in any one of its adjusted positions, a leg section adjacent to the side of each supporting plate, and means securing the outwardly and curved flanges of said supporting plates to the back edges of the corresponding and adjacent leg portions.

ALBERT T. RONK.
